US0D1105136S

(12) **United States Design Patent** (10) Patent No.: **US D1,105,136 S**
 Adawi et al. (45) Date of Patent: ** Dec. 9, 2025

(54) **DISPLAY SCREEN OR PORTION THEREOF WITH ICON**(71) Applicant: **Biosense Webster (Israel) Ltd.**, Yokneam (IL)(72) Inventors: **Eid Adawi**, Tur'an (IL); **Avigdor Rosenberg**, Kiryat Tivon (IL)(73) Assignee: **Biosense Webster (Israel) Ltd.**, Yokneam (IL)(**) Term: **15 Years**(21) Appl. No.: **29/987,542**(22) Filed: **Jan. 24, 2025**
